UNITED STATES PATENT OFFICE.

HARVEY A. BEASLEY, OF BARTLETTSVILLE, OKLAHOMA.

ROPE-KNIFE.

No. 923,482.

Specification of Letters Patent.

Patented June 1, 1909.

Application filed September 18, 1908. Serial No. 453,624.

To all whom it may concern:

Be it known that I, HARVEY A. BEASLEY, a citizen of the United States, residing at Bartlettsville, in the county of Washington and State of Oklahoma, have invented certain new and useful Improvements in Rope-Knives, of which the following is a specification.

My invention relates to an improvement in rope knives, and the object of this invention is, as the name implies, to provide an improved means for cutting the lower end of a wire rope or cable as close as possible to the rope socket, whereby the rope or cable may be drawn out of the well preparatory to fishing for tools.

My invention consists in a two-part tool, having inclined adjacent faces slidably connected with each other with an orifice lengthwise through the two-part tool whereby the sudden raising and lowering of the rope knife causes a severance of the rope due to the sliding action of one part upon the other.

My invention further consists in certain novel features of construction and combinations of parts, which will hereinafter be described and pointed out in the claims.

In the accompanying drawings:—Figure 1 is a view of one form of the invention. Fig. 2 is a horizontal section through the upper section on line A—A of Fig. 1. Fig. 3 is a similar view on the line B—B of Fig. 1. Fig. 4 shows another possible form of the invention. Fig. 5 is a view showing the removable knives.

The numerals 1 and 2 represent the upper and lower members or sections of the rope knife illustrated in Figs. 1, 2, and 3. These members are open on opposite sides as at 3 and 4, and as illustrated in Figs. 2 and 3 to receive the rope or cable C. The adjacent ends of these members 1 and 2 are inclined as at 5, whereby the two members upon coming together have a shearing action, and the sharp or acute angular formation at 6 and 7, constitute blades which cut the cable equally from opposite sides toward the center as between a pair of shears. The upper member with the jars and other tools above, is of sufficient weight so that as a rule a single drop for a very limited distance is sufficient to cause a complete severance of the rope or cable.

The members 1 and 2 are connected together by connecting rods or links 8, 8, one on each side as shown in Figs. 1 and 2, one

end, preferably the lower end of each link, being pivoted to the lower section 2 by means of a bolt 9, and studs 10, 10, on the other member are located in and adapted to move freely in the elongated slots 11, 11, in the links, whereby the operation of the two members is determined by the length of these slots.

In the construction illustrated in Fig. 4, the inclining surfaces are dove-tailed together, thus having purely a sliding connection with each other, instead of a drop and slide as in Fig. 1.

While my improved rope knife may be made entirely of steel, it is perfectly feasible to make it of softer metal in which event the knives illustrated in Fig. 5 would be made of steel and secured at the sharp angular edges 6 and 7.

In operation, when it is desired to cut a rope or cable, my improved knife is mounted upon the latter at the surface, and lowered to the rope socket with the string of tools above. Then when the lower section strikes the upper end of the rope socket, said section is suddenly stopped, and the upper section continues on, and as the inclining adjacent ends come together, the upper section continues on in a laterally shearing action, thereby severing the cable. If not cut by this first operation, it is only necessary to raise the tools a few inches, and again drop them, as many times as necessary to cut the rope or cable. In this way, I have provided a simple and effectual means for accomplishing the results desired by a tool of this character.

It is evident that other slight changes might be resorted to in the form and arrangement of the several parts described without departing from the spirit and scope of my invention, and hence I do not wish to limit myself to the exact construction herein set forth, but:

Having fully described my invention, what I claim as new and desire to secure by Letters Patent, is:

1. A rope knife comprising two members having longitudinal grooves therethrough to receive the cable to be cut, the members constructed with inclined ends and adapted to move diagonally with respect to each other, whereby to sever the cable.

2. A rope knife comprising two members having aligned grooves therethrough to receive the cable to be cut, and provided with inclining adjacent ends adapted to have a

sliding and shearing action when the members come violently together which results in the severance of the cable.

3. A rope knife comprising two members having inclining adjacent ends which cause the sections to move transversely in opposite directions when abutting each other, and means for limiting the movement of said sections with respect to each other.

10 4. A rope knife comprising two members having inclining adjacent ends, each member constructed and adapted to receive a rope

or cable to be severed, and links having a limited sliding connection with one member and secured to the other member, whereby to permit the members to have a limited movement with respect to each other. 15

In testimony whereof I affix my signature in presence of two witnesses.

HARVEY A. BEASLEY.
